US00D959393S

(12) **United States Design Patent** (10) Patent No.: **US D959,393 S**
 Sugiura et al. (45) Date of Patent: ** Aug. 2, 2022

(54) **CEILING HEATER FOR SUBSTRATE PROCESSING APPARATUS**

(71) Applicant: **KOKUSAI ELECTRIC CORPORATION**, Tokyo (JP)

(72) Inventors: **Shinobu Sugiura**, Toyama (JP); **Tetsuya Kosugi**, Toyama (JP); **Yuya Yoshimura**, Toyama (JP); **Takuto Shoji**, Toyama (JP)

(73) Assignee: **KOKUSAI ELECTRIC CORPORATION**, Tokyo (JP)

(**) Term: **15 Years**

(21) Appl. No.: **29/773,979**

(22) Filed: **Mar. 12, 2021**

(30) **Foreign Application Priority Data**

Sep. 24, 2020 (JP) ..... 2020020257 D

(51) LOC (13) Cl. 13-03

(57) **CLAIM**

The ornamental design for a ceiling heater for substrate processing apparatus, as shown and described.

DESCRIPTION

FIG. 1 is a front, top and right side perspective view of a ceiling heater for substrate processing apparatus showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view.

1 Claim, 4 Drawing Sheets
